UNITED STATES PATENT OFFICE

NUNZIO PAGANELLO, OF BROOKLYN, NEW YORK

MOUNTING FOR DOLLS' EYES

Application filed March 27, 1929. Serial No. 350,316.

This invention relates to an improvement in mountings for dolls' eyes and has for an object to provide means by which the eyes may be readily and easily inserted in position in their sockets, or removed therefrom without disturbing the cement or other fastening means which secures the mounting in the doll's head.

Another object consists in providing a mounting which may be permanently fixed in the doll's head immediately after the head is formed or molded and before the head is painted and completely finished.

Another object consists in providing a mounting having an eye carrying device yieldingly held in position therein and arranged to be removed or replaced without the aid of a skilled operator, thereby materially reducing the cost of manufacture and increasing the speed of production.

Another object consists in providing a mounting and eye carrying device which is simple in construction, efficient and economical to manufacture.

Another object consists in providing certain improvements in the form, construction and arrangement of the several parts whereby the above named and other objects may be effectively attained.

A practical embodiment of my invention is represented in the accompanying drawings, in which:

Fig. 1 represents a vertical section of a doll's head looking toward the front and showing my improved structure applied thereto.

Fig. 2 represents a vertical section taken in the plane of the line II-II of Fig. 1 looking in the direction of the arrows.

Fig. 3 represents a horizontal section taken in the plane of the line III-III of Fig. 1 looking in the direction of the arrows.

Fig. 4 represents a side elevation, partly in section, of my mounting showing the eye carrying device partly removed.

Fig. 5 represents a similar view with the eye carrying device in another position.

Fig. 6 represents a front elevation of the mounting, and

Fig. 7 represents a front elevation of the eye carrying device.

In the known methods of applying eye mountings to dolls' heads, it has been necessary to form or mold, paint and completely finish the doll's head before the mounting could be set therein or applied to the head. It has also been necessary to exercise considerable care and skill in setting and adjusting the eyes in the sockets in the head after the paint, etc. has become dried and hardened. This operation is very costly and requires skilled labor to perform the same. Furthermore, a long period of time must elapse before the product is ready for the eye mounting, after which it must then wait another period for the cement to dry and harden which secures the eyes and their mounting in the head.

With my improved structure one portion of the mounting is cemented in place after the head is formed and molded and before the head is painted and finished. The form is then painted and completely finished, so that the eye carrying device may be readily and quickly inserted as soon as the paint has become dry and hard. The operation of inserting the eye carrying device is very simple and accomplished by even an unskilled operator.

The mounting which is fixed in the doll's head after it is formed or molded comprises, a rigid flat strip-like member 1, and a spring actuated member 2, which members are secured together at their upper ends by any well known means, in the present instance, I have shown rivets 3. The member 1 has its upper end bent over at 4 to assist in keeping the members in position. The lower end of the member 1 is bent at 5 to form a guide and stop by which the member is positioned in the doll's head 6. This member 1 is also provided with outwardly projecting ears 7, 8 disposed on opposite sides and arranged to straddle the spring actuated member 2. The ears 7, 8 are provided with open slots 9, 10 and curved lower ends 11, 12 respectively, the purpose of which will be hereinafter explained. The spring actuated member 2 is provided, at a point in line with the slots 9, 10 of the

member 1, with a transversely arranged recess 13, the opening of which is yieldingly held against the member 1. The lower end of the member 2 is curved outwardly to form a guide 14 which coacts with the guide 5 of the member 1.

An eye carrying device comprises a horizontally disposed shaft 15 having secured at its opposite ends eye-ball shells 16, 17, which 10 may be adjusted rotatively and longitudinally thereon, in any well known or approved manner. This shaft 15 is mounted in the slot 9, 10 of the member 1 and journaled in the recess 13 of the spring actuated member 2. A 15 counterbalance 18 is secured to the shaft 15 by means of depending arms 19, 20, which arms are arranged to move on opposite sides of the members 1, 2 and adjacent the ears 7, 8. This counterbalance serves to regulate the position of the eye-ball shells 16, 17 with respect 20 to the sockets 21, 22 in the doll's head 6.

In order to secure the shaft 15 in position between the members 1, 2 and against unintentional displacement, I provide a spring actuated arm 23, one end of which is secured to the fixed end of the spring actuated member 2 by means of the rivet 3, while the free end is arranged to press against the inner wall of the curved guide 14, thereby tending to keep 30 the member 2 in the intimate contact with the member 1.

When it is desired to remove the eye carrying device, for purpose of replacement or adjustment, the spring actuated member 2 is 35 moved outwardly against the tension of its spring and the spring actuated arm 23, so that the shaft 15 may be lifted from the slots 9, 10 in the ears 7, 8 and then removed from the recess 13 in the member 2, as shown in Fig. 40 4, after which the shaft may be moved vertically in a downward direction so as to ride on the ears 7, 8 until the shaft passes from between the curved guides 5, 14 of the members 1, 2.

45 In order to replace the eye carrying device, the portion of the shaft 15 between the depending arms 19, 20 is moved upwardly into the curved guides 5, 14 and caused to ride upwardly on the curved ends 11, 12 of the ears 50 7, 8 until it falls into the slots 9, 10, whereupon the tension of the spring actuated member and arm is released and the transverse recess 13 of the member 2 brought into engagement with the shaft 15, thereby forming 55 a journal in which the shaft 15 may rock.

To limit the rocking movement of the shaft 15 in one direction, I provide stops 24, 25, which extend upwardly from the shaft and are arranged to be brought into engagement 60 with the inner wall of the doll's head 6, as shown in dotted outline in Fig. 2. The shaft 15 is also limited in its rocking movement in the other direction by the counterbalance 18, which engages the inner wall of the doll's head as shown in Fig. 2.

It is evident that various changes may be resorted to in the form, construction and arrangement of the several parts without departing from the spirit and scope of my invention; and hence, I do not intend to be limited to the details herein shown and described, except as they may be included in the claims. 70

What I claim is:—

1. A mounting for dolls' eyes comprising, a member fixed in the doll's head, said member including a rigid portion having its lower end bent forwardly to form a stop arranged to engage the doll's head for positioning the member therein, said portion having rearwardly disposed ears provided with open slots and a yielding portion secured at one end to said rigid portion and movable between the ears, and an eye carrying device including a shaft removably mounted in said slots in the ears of the rigid portion. 80

2. A mounting for dolls' eyes comprising, a member fixed in the doll's head, said member including a rigid portion having its lower end bent forwardly to form a stop arranged to engage the doll's head for positioning the member therein, said portion having rearwardly disposed ears provided with open slots, a yielding portion having a transverse recess formed therein and disposed to be moved between said ears, said yielding portion being secured at one end to the rigid portion, and an eye carrying device including a shaft removably mounted in said slots in the ears of the rigid portion and the transverse recess of the yielding portion. 90

3. A mounting for dolls' eyes comprising, a member fixed in the doll's head, said member including a rigid portion provided at one end with a curved stop arranged to engage the doll's head for positioning the member therein, said portion having ears provided with open slots, a flat yielding portion having its lower end curved outwardly and its upper end secured to said rigid portion, and an eye carrying device including a shaft removably mounted in said slots in the ears of the rigid portion, the exterior surface of said curved stop on the rigid portion and the curved lower end of the yielding portion being disposed in opposite directions to form guides therebetween for the insertion of the eye carrying shaft to the slots in the ears. 110

4. A mounting for dolls' eyes comprising, a member fixed in the doll's head, said member including a rigid portion provided at one end with a curved stop arranged to engage the doll's head for positioning the member therein, said portion having ears provided with open slots, the edges of said ears being shaped to form guides to said slots, a flat yielding portion having its lower end curved outwardly and its upper end secured to said rigid portion, and an eye carrying device including a shaft removably and yieldingly mounted in said slots in the ears 120

125

130

of the rigid portion, the exterior surface of said curved stop on the rigid portion and the curved lower end of the yielding portion being disposed in opposite directions to form 5 guides therebetween for the insertion of the eye carrying shaft to the slots in the ears.

5. A mounting for dolls' eyes comprising, a member fixed in the doll's head, said member including a rigid portion provided at 10 one end with a curved stop arranged to engage the doll's head for positioning the member therein, said portion having ears provided with open slots, the edges of said ears being shaped to form guides to said slots, a 15 flat yielding portion having a transverse recess formed therein and disposed to be moved between the ears, said yielding portion having its lower end curved outwardly and its upper end secured to said rigid portion, and 20 an eye carrying device including a shaft removably mounted in said slots in the ears of the rigid portion and the transverse recess of the yielding portion, the exterior surface of said curved stop on the rigid portion and 25 the curved lower end of the yielding portion being disposed in opposite directions to form guides therebetween for the insertion of the eye carrying shaft to the slots in the ears.

6. A mounting for dolls' eyes comprising, 30 a member including a flat rigid portion and a flat yielding portion secured together at one end, said flat rigid portion being arranged to be fixed in the doll's head and contact therewith throughout its length, rear- 35 wardly extended ears projecting from the side edges of said flat rigid portion and spaced apart to form open slots, and an eye carrying member including a shaft removably mounted in said slots and arranged to 40 be engaged by said flat yielding portion between the ears.

7. A mounting for dolls' eyes comprising, a member including a flat rigid portion and a flat yielding portion secured together at 45 one end, said flat rigid portion being arranged to be fixed in the doll's head and contact therewith throughout its length, rear- 50 wardly extended ears projecting from the side edges of said flat rigid portion and spaced apart to form open slots, said flat yielding portion being bent to form a trans- 55 verse recess therein and disposed to register with the slots, and an eye carrying member including a shaft removably mounted in the slots and arranged to be yieldingly embraced by said transverse recess in the yielding portion.

In testimony that I claim the foregoing as my invention, I have signed my name this 60 26th day of March, 1929.

NUNZIO PAGANELLO.
